UNITED STATES PATENT OFFICE

2,433,406

RACK

Mary W. Standlee, Washington, D. C.

Application November 20, 1943, Serial No. 511,009

2 Claims. (Cl. 211—126)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to racks, and more particularly to those which are mounted on wheels and used in hospitals, etc., for holding books and the like.

It is among the objects of the present invention to provide an improved rack of the class described which will hold a sizable number of books, periodicals, etc., in such manner that the same may be conveniently selected by those in confined areas, such as bed patients in hospitals. More specifically, the present invention contemplates a wheeled rack comprising lower and upper storage portions in which the upper storage portion is rotatable, the rack as a whole being small in size and relatively light in weight.

Another object is the extreme maneuverability of the rotatable upper portion of the rack as well as the lower wheeled portion thereof.

Still another object is the attainment of the foregoing without sacrifice of compactness and/or storage facilities.

To the foregoing and other useful ends, the invention comprises structural features herein-after described and claimed, and shown in the accompanying drawings, in which:

Figure 1 is a perspective of the rack of the present invention in which the same has been loaded with books and magazines with a view toward serving persons in confined areas, such as bed patients in hospitals, etc.;

Figure 2 is a plan of the rack of Figure 1, prior to loading;

Figure 3 is a sectional elevation of the showing of Figure 2;

Figure 4 is a view similar to that of Figure 3 but taken at right angles thereto.

Referring more particularly to the drawings, the rack of the present invention comprises a wheeled lower storage portion A, on which there is mounted a rotatable upper storage portion B.

As shown more clearly in Figures 3 and 4, the wheeled lower portion A comprises four vertical corner posts 2 which are disposed in oblong relationship and connected together adjacent their lower ends by lower horizontal side members 3 and lower horizontal end members 4. Disposed on the upper edges of the lower horizontal side members 3 and the lower horizontal end members 4, and connecting the same together, is a shelf 5. In addition, the shelf 5 may be directly connected to the corner posts 2. Adjacent their

2

upper ends, the corner posts 2 are connected together by upper horizontal side members 7 and upper horizontal end members 8.

Disposed in flush relationship with the upper edges of the upper horizontal side and end members 7 and 8, respectively, and connecting the same together, is a table member 9. This table member 9 may also be directly connected to the corner posts 2.

10 The lower ends of the four vertical corner posts 2 carry the wheels 10 of the wheeled lower portion A. These wheels 10 are preferably rubber-tired and mounted on antifriction bearings. The pair of wheels at one end of the rack may be carried on non-rotatable hangers 11; while at the other end of the rack the wheels are carried on casters 12 which comprise curved off-set arms 13. This arrangement provides extreme maneuverability of the rack as a whole.

20 The rotatable upper portion B of the rack of the invention comprises four vertical corner posts 15 which are disposed in oblong relationship and connected together adjacent their lower ends by lower horizontal side members 16 and lower horizontal end members 17. Disposed in flush relationship with the lower edges of the lower horizontal side and end members 16 and 17, respectively, and connecting the same together, is an intermediate or bottom shelf 18. This bottom shelf 18 may also be directly connected to the corner posts 15.

25 Adjacent their upper ends the corner posts 15 are connected together by upper horizontal side members 19 and upper horizontal end members 20. The lower edges of these upper horizontal side and end members 19 and 20, respectively, receive in flush relationship, and are connected together by a top shelf 21. Like the bottom shelf 18, this top shelf 21 may also be directly connected 30 to the corner posts 15.

35 The mounting for the rotatable upper storage portion B comprises a pair of large disks 23, one being centrally disposed on the bottom of the bottom shelf 18, and the other being correspondingly disposed on the top of the table member 9 of the wheeled lower portion A. These large disks 23 may be formed of a suitable wood (for example, maple); and in such case be retained in place by means of glue. Between the large 40 disks 23, which, as shown in the drawings, are of such size as to be substantially coextensive with the areas of the members by which they are carried, there is concentrically disposed a comparatively small washer 24. The washer 24, disks 23, and the elements which carry the latter,

are all centrally bored to receive a bolt 25, the head of which may be countersunk in the upper surface of the bottom shelf 18 of the rotatable upper portion B. The lower, and threaded, end of the bolt 25 projects beyond the underside of the table member 9 of the wheeled lower storage portion A and receives a nut 26.

According to the foregoing construction and arrangement there is provided a sturdy, although inexpensive, rack which is possessed of many desirable features. The rotatable upper storage portion B provides top and bottom shelves which are well-suited to hold books or other articles from which a selection is to be made. The combination of the four corner posts with the lower horizontal side and end members 16-17 and the upper horizontal side and end members 19-20 permits maximum visibility of the contents of the shelves 18 and 21. In addition, the wheeled lower portion A of the rack is preferably of such height as to permit the rotatable upper portion B to clear the top of a hospital bed, thus providing increased accessibility for bed patients.

By superposing the shelf 5 on the upper edges of the lower horizontal side and end members 3-4 of the wheeled lower portion A, the increase in the area of the shelf is accompanied by increased visibility and accessibility, at least from the ends of the rack as shown in Figure 1.

One of the upper horizontal end members 8 of the wheeled lower portion A of the rack carries a pair of horizontally extending spaced individual handles 21 which are sufficiently large as to be useful, but of such size, shape and disposition as to consume a minimum of space.

According to a preferred embodiment the wheeled lower portion A is provided on either side with a side panel 28 which is substantially flush with the inner faces of the most adjacent of the corner posts 2; while extending in parallelism therewith, and connected across the outer faces of each of the said posts, is a pair of spaced horizontal side strips 29. These elements form storage spaces which may be conveniently used for magazines, etc.

At times it may be desirable to prevent the rotation of the rotatable upper storage portion of the rack; and for this purpose there may be provided between it and the wheeled lower storage portion A, a bolt-and-receiver combination, as shown at 30 in Figure 1.

Another refinement may take the form of a writing board 31 which is slidably disposed in a slot 32 in one of the upper horizontal side or end members 7-8 of the wheeled lower portion A of the rack.

Other modes of applying the principles of the invention may be employed, changes being made as regards the details described, providing the features stated in any of the following claims, or the equivalent of such, be employed.

Having described my invention, what I claim as new and desire to secure by Letters Patent is:

1. In a wheeled library rack for hospitals and the like, a lower rectangular box-like storage portion and an upper rectangular box-like storage

portion rotatably mounted thereon each comprising four vertical corner posts with horizontally aligned transverse members connecting the lower ends of the corner posts and separate horizontally aligned transverse members connecting the upper ends of the said corner posts, shelving disposed upon the upper edges of the lower transverse members of the lower storage portion, separate shelves connecting the upper and lower transverse members, respectively, of the upper storage portion, the shelves of the upper storage portion being substantially flush with the bottom edges of their respective transverse members to provide trays, and means mounted on the rack for releasably locking the upper storage portion on the lower storage portion.

2. In a wheeled library rack for hospitals and the like, a lower box-like storage portion comprising four vertical corner posts with lower horizontally aligned transverse members connecting the lower ends of said corner posts, and separate upper horizontally aligned transverse members connecting the upper ends of said corner posts, a bottom shelf disposed on the upper edges of said lower transverse members, a table member mounted on and disposed in flush relationship with the upper edges of said upper horizontally aligned transverse members, an upper box-like storage portion rotatably mounted on said table, said upper storage portion including four separate vertical corner posts with lower horizontally aligned transverse members connecting the lower ends of said last-mentioned corner posts and upper horizontally aligned transverse members connecting the upper ends of the corner posts of said upper storage portion, an intermediate shelf mounted on and disposed in flush relationship with the lower edges of said lower transverse members of said upper storage portion, a top shelf mounted on and disposed in flush relationship with the lower edges of said upper horizontally aligned transverse members of said upper storage portion, and complementary means mounted on said upper and lower storage portions for releasably locking said upper storage portion against relative rotational movement on said lower storage portion.

MARY W. STANDLEE.
